NEAL T. MCKEE, OF BRONXVILLE, NEW YORK

LOCOMOTIVE SMOKE-BOX ARRANGEMENT

Application filed October 14, 1926. Serial No. 141,621.

In modern locomotives a large number of elements of an auxiliary nature are located in the smoke-box including usually a superheater, which for purposes of maintenance and repair must be made as accessible as possible. Accessibility of the rear of the smoke-box is also desirable in order that the forward flue sheet of the boiler may receive proper attention, and heretofore this desired accessibility has not been obtained because of the projection of the lower portion of the locomotive stack through the central portion of the smoke-box, the presence of the screens forming the usual spark arrester, the damper generally used in connection with the superheater installation, and the steam pipes passing through the smoke-box from the superheater header to the engine steam chest.

With the smoke-box arrangement as heretofore constructed, many of these elements must be partially or wholly removed before access can be had to the flue sheet of the boiler and the superheater units, and it is the principal object of my invention to provide a smoke-box arrangement whereby the forward flue sheet is made readily accessible. More specifically, my invention contemplates the construction of the locomotive stack and the screens forming the spark arrester as a unit removable from the smoke-box through the upper wall thereof. Other and more detailed objects of the invention will appear as the following detailed description of the embodiments of my invention illustrated in the accompanying drawings proceeds.

In the drawings, Fig. 1 is a central vertical section taken through a smoke-box constructed in accordance with my invention. Fig. 2 is a composite view of the structure shown in Fig. 1, the right-hand portion being shown in top plan view and the left-hand portion being shown in horizontal section. Fig. 3 is a transverse vertical section taken through the smoke-box, with a portion of the stack cut away. Fig. 4 is an enlarged detail of construction. Fig. 5 is a view similar to Fig. 1 of a second form and Fig. 6 is a composite sectional view, the right-hand portion of which is taken along the line 6^a—6^a.

and the left-hand portion of which is taken along the line 6^b—6^b.

Referring now to Fig. 1, the main boiler shell 10 is extended forward of the flue sheet 11 and has attached thereto a sheet 12 forming the smoke-box 13 which is closed at its forward end by the usual form of front end door (not shown).

The usual form of fire tube superheater is shown, having heating units 14 extending into boiler flues 15 and receiving saturated steam from the dry pipe 16, which after being distributed through the saturated steam header 17, is discharged from the superheated steam header 18 to the engine steam pipes 19. The engine exhaust pipe 20 is located in the usual position at the bottom of the smoke-box and terminates preferably though not necessarily in a separate nozzle or tip 21.

The upper portion of the smoke-box sheet 12 is cut away to form a comparatively large opening 22 and the smoke-box is built up by means of suitable side members 23 so that a plane opening or port is formed in the top 75 of the smoke-box directly above the exhaust pipe 20. A cover plate 24 is secured to the flanged portions of the members 23 around the opening 22 in a manner to provide a gas-tight joint, and is provided with a central 80 opening for the reception of the locomotive stack. The stack 25 may be of the usual form, supported by a flange 26 and having the usual depending skirt portion 27 extending into the smoke-box. Instead of being secured to the sheet forming the smoke-box wall, the supporting flange 26 of the stack is, in the form I have shown, permanently secured to the cover plate 24. The use of the separate cover plate 24 is obviously not essential, as the flange 26 may be cast to fit the perimeter of the opening 22, but the form shown is preferable because of its lighter weight.

A number of webs 28 are provided which 95 extend downwardly from the lower end of the skirt 27 to terminate in a ring 28^a which fits over the tapered nozzle 21 to support the stack and also to prevent lateral displacement. The screen 29 forming the spark 100

arrester surrounds the stack and is made approximately cylindrical in form, with the diameter of the screen small enough to enable it to pass through the opening 22 in the 5 top of the smoke-box, the bottom of the screen being attached to the ring 28^a surrounding the nozzle 21.

In order to provide the proper baffling within the smoke-box a pair of vertical baffle 10 plates 30 (see Fig. 2) are permanently mounted in the smoke-box ahead of the superheater headers and through these baffle plates the steam connections leading to the engine pass. As will be seen from Fig. 2, the baffle plates 15 30 extend inwardly from the sides of the smoke-box approximately half way to the center line of the smoke-box and the intervening space between the inner edges of these baffles is closed by a removable baffle plate 31 20 attached to the cover plate 34 and the screen 29.

As illustrated in Fig. 4, the baffles 30 have attached to them, preferably by welding, the 25 guide strips 32 between which the edges of the baffle plate 31 are received, this construction forming a substantially gas-tight sliding joint.

At their lower ends, the baffle plates 30 are attached to a horizontal baffle 33 which extends 30 entirely across the lower portion of the smoke-box to a point forward of the exhaust pipe, between which and the baffle a gas tight joint is provided.

From the foregoing description it will be 35 apparent that the smoke-box may be cleared of the obstruction formed by the stack and spark arrester by merely unbolting the cover plate 24 from the smoke-box and lifting both stack and screen as a unit through the opening 40 in the top of the smoke-box. With these elements removed it will further be apparent that an opening of sufficient size is provided between the baffles 30 and above the baffle 33 to afford easy access to the superheater elements and to the flue sheet of the boiler. 45

In Fig. 5 I have shown a different form of construction in which my invention is employed in a smoke-box arrangement using a superheater damper and which is designed to 50 accommodate a feed water heater mounted above the smoke-box. In this form the arrangement of boiler shell 10', flue sheet 11', smoke-box sheet 12' and the several elements forming the superheater are essentially the 55 same as described in connection with Fig. 1, except that in this form the superheated steam header 18' is provided with steam outlets at the ends thereof from which the engine steam pipes 19' lead through suitable openings in 60 the sheet 12' to the outside of the smoke-box.

The smoke-box sheet 12' is flattened at the top to reduce the height of the smoke-box for the accommodation of the feed water heater, indicated at 34, and is provided with an opening 65 22' in this flattened portion over the en-

gine exhaust pipe 20'. As in the form previously described, the opening 22' is closed by a bolted cover plate 24' through which the stack 25' passes, the latter being suitably secured to the plate 24' by the flange 26'. The 70 stack skirt 27' has attached thereto a plurality of webs 28' which terminate in a nozzle tip 21' adapted to seat in the opening of the exhaust pipe 20'.

The spark arrester is formed by a rectangular screen attached to the cover plate 24' and having its rear wall formed by a baffle plate 31' removably secured between the baffle plates 30' in the same manner as in the form shown in Fig. 1. Horizontal baffles 33^a and 33^b are provided which extend inwardly from the sides of the smoke-box and are joined by the bottom section 33^c of the spark arrester behind which a damper 35 is mounted. The front of the spark arrester is formed by a 85 member 36 hinged at 37 and composed of a front screen and V-shaped side screens, the latter being supported by inverted L-shaped members 37^a. The upper forward end of member 36, when in the position shown in 90 Fig. 5, rests against a baffle plate 38 mounted in the upper forward portion of the smoke-box and, as will be readily apparent, the front screen member 36 may be swung about the hinge 37 so that in its retracted position the 95 entire screen may be removed through the opening 22'.

In the form just described, it will be apparent that the same advantages are secured as in the form previously described and in 100 addition a larger area of screen surface may be secured.

The foregoing embodiments of my invention are to be taken as illustrative only, as it is obvious that many changes in the details 105 of construction may be made within the scope of the invention as defined in the appended claims.

I claim:

1. In apparatus of the class described, the combination with a locomotive smoke-box shell having an opening in the top thereof, of a cover plate removably secured to said shell around said opening, a stack secured to said cover plate and passing therethrough, and a spark arresting screen attached to said cover plate and surrounding the portion of the stack within the smoke-box, said stack and screen being removable through said opening. 115

2. In apparatus of the class described, the combination with a locomotive smoke-box having an opening in the top thereof and a rear wall formed by the boiler flue sheet, of a stack removably mounted in said smoke-box and passing through said opening, a spark 120 arresting screen located in said smoke-box around said stack, and a sectional baffle located transversely of said smoke-box between said stack and said flue sheet, said baffle comprising end sections secured to the 125 130

wall of said smoke-box and a center section slidably mounted between said end sections, said stack, screen and center baffle section comprising a unit removable from said

5 smoke-box through said opening.

3. In apparatus of the class described, the combination with a locomotive smoke-box having an opening in the top thereof, of a stack removably mounted in said smoke-
10 box and a spark arresting screen around said stack, said screen when in normal position occupying a space greater in section than the area of said opening and comprising a re-
tractable portion whereby the sectional di-
15 mensions of said screen may be made smaller than the dimensions of said opening for pur-
poses of removal therethrough.
